UNITED STATES PATENT OFFICE.

CHARLES H. THURSTON, OF MARLBOROUGH, NEW HAMPSHIRE.

SEWING-MACHINE SHUTTLE.

SPECIFICATION forming part of Letters Patent No. 246,839, dated September 6, 1881.

Application filed November 5, 1880. (No model.)

To all whom it may concern:

Be it known that I, CHARLES H. THURSTON, of Marlborough, county of Cheshire, State of New Hampshire, have invented a new and useful Improvement in Sewing-Machine Shuttles, of which the following description, in connection with the accompanying drawings, is a specification.

This invention in shuttles for sewing-ma-
10 chines relates to means for retaining the bob-
bin-holder in position when extended across
the bobbin; also, to improvements in the con-
struction of the tension device, and in the man-
ner of holding it in place in the shuttle.

15 The shuttle herein shown, of usual shape, has
its bobbin held in the shuttle-chamber by a
holder made as a vibratory finger extended
partially across the head of the bobbin, the
said finger projecting from a pin or shank fitted
20 loosely in a hole in the shuttle-body, said hole
being parallel with the axis of the bobbin. The
wall of the shuttle at one edge of the bobbin-
receiving chamber is provided with a notch or
recess having an inclined or beveled side, the
25 said notch receiving and retaining the holder
when in proper position to keep the bobbin in
the shuttle. The holder when in this recess is
brought so far within the shuttle-body that the
loop of needle-thread cannot be caught by the
30 shuttle when passing through it, and when the
bobbin is to be removed the mere turning of
the holder causes it to act upon the inclined
side of the recess in which it is placed, thus
lifting the holder in the direction of the axis
35 of its shank. The curved end of the bow-
spring, which forms part of the tension device,
enters a groove in the wall of the shuttle, which
prevents that end of the spring from being
turned out of the shuttle.

40 Figure 1 represents, in front view, a shuttle
made in accordance with my invention; Fig. 2,
a side elevation, partially broken out, to show
the shank of the holder and the groove to re-
ceive the curved end of the bow-spring em-
ployed for producing tension; Fig. 3, a cross-
45 section of Fig. 2 on the dotted line xx , Fig. 1;
and Fig. 4 shows the bow-spring removed from
the shuttle.

The body a of the shuttle is of usual shape,

and has a chamber at its side to receive the 50
headed bobbin b , a pin or post, c , being prefer-
ably employed to serve as a center about which
the bobbin may be rotated by the thread. The
bobbin is held in place in the chamber of the
shuttle by a holder, d , shown as a finger hav- 55
ing a right-angled shank, 2, screw-threaded at
3, and extended into an opening in the shuttle-
body parallel with the axis of the bobbin-re-
ceiving chamber. The shank of this holder has
placed upon it a spiral spring, 5, and then a 60
threaded nut, 4, so that by turning the said
nut the force of the spring is made sufficient to
keep the holder in the recess made for it and
hold the bobbin in its chamber in the shuttle.
The thread in its passage about the shuttle 65
must touch only the wall of the shuttle, and
the tension devices and bobbin-holder must be
wholly contained within the outline of the shut-
tle-body, or else the loop of needle-thread will
be caught and held and defeat proper sewing. 70

To obviate catching the needle-thread, the
body of the shuttle, between the bobbin-cham-
ber and shank 2 of the holder, is cut away or
notched to form a recess at the face of the shut-
tle to receive the holder when in the position 75
Figs. 1 and 2, the position it occupies when
sewing, the spring 5 retaining the holder in the
said notch.

When the bobbin is to be removed or a new
one inserted in the shuttle, the holder is lifted 80
by the operator and turned aside or laterally
from above the bobbin, as in Fig. 3, and during
such movement the holder acts against the in-
clined edge n of this recess and is lifted, the
shank of the holder then moving longitudinal- 85
ly, its nut 4 compressing the spring 5.

The tension device placed in a recess, 16, at
the face of the shuttle, is composed of a U-
shaped or bow spring, h , having broad ends 14
15, the outer side of the end 14 having a smooth 90
face to bear upon one side of the thread 18, led
between it and the inner wall of the recess op-
posite the smooth face of the end 14, the said
wall being also made smooth and hard.

The narrow curved end 10 is made to enter 95
a groove, 13, (shown in section, Fig. 2, and in
dotted lines, Fig. 1,) which acts to prevent that
end of the spring from being turned out of the

shuttle. After leaving the bobbin the thread is led into the slots 19 20, thence between the face of the end 14 of the spring and the inner smooth wall of the shuttle, and out through a hole (shown in dotted lines, Fig. 1,) at the top of the shuttle.

The tension or pressure of the spring on the thread may be increased or decreased by the shouldered screw 21, which acts on the arm 15 10 of the spring. The screw 21 to be turned may be engaged by a screw-driver at either end. The spring 21 has two opposite holes, 22 and 23, to receive the screw 21, it thus serving to hold the main part of the spring in place.

15 I claim—

1. The shuttle-body having the beveled or inclined notch at the edge of its bobbin-chamber, combined with the axially-movable bobbin-holder *d*, provided with a shank, 2, and 20 adapted to rest in the said notch, and with the nut 3 and spring to act upon the shank of and

keep the holder in the said notch of the shuttle-body to retain the bobbin in place, the said holder being lifted by the incline of the shuttle-body when being turned aside for the removal 25 of the bobbin, substantially as described.

2. The shuttle-body provided with the recess 16 and the groove 13 and the U-shaped or bow spring *h*, having a portion, 10, thereof entered into the said groove, combined with 30 the adjusting-screw extended through holes in the said spring, the screw holding the spring in the said recess, to operate substantially as shown and described.

In testimony whereof I have signed my name 35 to this specification in the presence of two subscribing witnesses.

CHAS. H. THURSTON.
